UNITED STATES PATENT OFFICE.

HENRY A. OWEN, OF WHITINSVILLE, MASSACHUSETTS, ASSIGNOR TO THE WHITIN MACHINE WORKS, OF WHITINSVILLE, MASSACHUSETTS, A CORPORATION OF MASSACHUSETTS.

NIPPER-MOTION DRIVE FOR COTTON-COMBERS.

1,157,033.

Specification of Letters Patent.

Patented Oct. 19, 1915.

Application filed October 26, 1909. Serial No. 524,691.

To all whom it may concern:

Be it known that I, HENRY A. OWEN, a citizen of the United States, and a resident of Whitinsville, in the county of Worcester and Commonwealth of Massachusetts, have invented certain new and useful Improvements in Nipper-Motion Drives for Cotton-Combers, of which the following is a full, clear, and concise specification sufficient to 10 enable any person skilled in the art to make and use the same.

The invention is a new construction and arrangement of parts of a nipper-motion drive for cotton combers, and seeks to improve the operation and smoothness of the running thereof, and particularly to reduce vibration in high speed cotton combers whereof the nipper-knives coöperate with fixed cushion plates and are required to alternate from open to closed condition with great rapidity. The results stated are accomplished by the combination with certain of the operating parts of the driving mechanism of a spring-yielding driving connection, the nature and relation of which to the said parts is hereinbelow fully explained and made the subject of the several claims appended hereto.

In the two sheets of drawings which form 30 a part of this specification, Figure 1 is a transverse section of portions of a high speed comber of the Heilmann type, as will be recognized by those familiar with this art, and shows sufficient of such machine to 35 illustrate the relation thereto of the drive motion, also shown, and constituting this invention. Figs. 2 and 3 are respectively side and front elevations of the nipper-lever and nipper-cam-lever and their interconnecting spring-yielding driving connection; and Fig. 4 is a front elevation of Fig. 1 with certain parts removed.

The frame of the combing machine illustrated comprises an upright standard 45 marked 1, which is one of several similar standards all carried by the horizontal girder 2 and forming with it the fixed frame work for the several combing heads of the machine. There is one such upright standard between each combing head and its next adjacent head. The combing heads are all of identical construction and each includes a nipper frame 3 carried on the upper part of the frame work, and provided with the

usual cushion plate 4. The nipper knife 5, which coöperates with the cushion plate, is carried on the ends of the knife levers 6 which are fulcrumed on a shaft 7, also carried by the nipper frame. The rear ends of the knife levers are connected with the nipper motion drive constituting this invention by means of the connecting rods 8. In the high speed comber, which is herein illustrated, the nipper-frame is stationary and holds its cushion plate permanently in a single operative position wherein its nipper knife coöperates therewith to hold the cotton during the combing and also the detaching operations, the said knife being oscillated on its shaft axis 7 from its open, upper position to its closed, lower position. It is required to exert sufficient nipping pressure on the cotton lap to prevent its being drawn from under it while being combed.

The parts whereby the projecting tuft, held by the nipper mechanism just described, is combed and thereafter detached and pieced and delivered are not shown in full, the same having no direct relation to the present invention. The location of 80 combing shaft however, is represented at 10 and the calender roll and sliver apron at 11 and 12 respectively.

The drive for the nipper motion above referred to comprises a longitudinal rock shaft 85 13 herein termed the nipper-shaft, which is journaled in the frame standards 1 and carries fast upon it a number of rearwardly extending nipper-shaft arms 14, one for each of the connecting rods 8, and also a forwardly extending operating lever arm 15 herein termed the nipper-lever. There may be secured to the nipper-shaft 13 as many rearward nipper-shaft arms 14 as may be desired to be operated by a single nipper lever 90 15, and their connection with their respective rods 8 may be made with facilities for adjustment as indicated in Fig. 1. The nipper shaft serves as a fulcrum bearing upon which the nipper lever oscillates the arms 14 100 and thereby the several connected nipper knives. The nipper lever itself is adapted to be actuated by means having the capacity of limited movement relatively thereto and against the tension of a suitable spring yielding connection, and for this purpose it is formed with a comparatively short stub arm 105 15^a and a relatively longer arm 15^b. The

end of the longer arm is provided with an offset ear 16 by which it is connected with one end of a heavy helical spring 17. The other end of the spring is connected to a 5 corresponding ear 18^b on a reciprocating member 18 which is positively driven, either directly or otherwise, from some rotary element of the comber, as for instance, the usual nipper cam 19 thereof. The said 10 positively-driven member 18, is preferably directly actuated by the nipper cam and formed as a usual cam lever which is fulcrumed on the nipper-shaft adjacent and parallel to the stub arm 15^a, so that it may 15 thus occupy the space between the two laterally projecting lugs 20 and 21 formed thereon. At the point marked 18^a it carries the cam roller engaged by the cam groove, and it is preferably extended downwardly from 20 this point, as shown, in order to accommodate the length of the spring. The said spring, however, can be variously adapted to the construction of the levers and the other parts, in obvious manner.

25 The cam-imparted motion of the lever 18 is transmitted to the nipper lever, in one direction, through the driving connection formed by the spring, and in the other direction through its engagement with an 30 abutment carried by the uppermost lug 20. Such an abutment may be formed by a set screw 22 tapped into the lug and hence adjustable. The driving movement transmitted through the spring serves to close 35 the nipper knives against their respective, fixed cushion plates, and accomplishes such effect without jar or tendency to rebound; the return movement, transmitted through the abutment 22, opens them. The adjustment 40 of the said abutment serves to determine the relative position of the nipper lever and its connected parts with respect to the position of the nipper cam, and when thus set the connections of the spring with its 45 attachment lugs 16 and 18^b are adjusted to put the spring under tension and thereby hold the cam-operated member against the abutment. As thus assembled the nipper lever and the positively driven cam lever 50 will be maintained in a substantially fixed relation but with the capacity of relative yielding movement of the one upon the other against the tension of the spring. Such movement of yield, however, may not take 55 place in normal operation of the comber to any appreciable extent or to any extent more than sufficient to absorb the shock and vibration and accommodate slight variations in the contour of the cam surface of the nipper cam. The counter abutment formed by 60 the lower lug 21, on the nipper lever, is

therefore seldom required and its main function is to maintain an approximately proper relationship of the cam-lever thereto during 65 the assemblage or overhauling of the machine.

I claim the following:

1. In a comber having several comber heads, the combination with nipper-knives of the respective comber heads, a common 70 nipper-shaft having fast thereon a number of nipper-shaft arms, and adjustable connections between said nipper-shaft arms and said nipper-knives, of a nipper-cam, a member reciprocated thereby, a common nipper-lever fast on said nipper-shaft and adapted 75 to be operated by said member to rock said shaft, one of the two last-recited elements having an adjustable abutment, and a normally-stressed spring-yielding driving connection between said elements holding said 80 adjustable abutment against the other of said elements and permitting the reciprocating member to move relatively to the nipper-lever during the normal operation of the 85 machine.

2. In a comber, the combination with nipper-knives of a number of combing heads, a nipper-shaft, and connections between said 90 nipper-shaft and nipper-knives, of a nipper-cam, a member reciprocated thereby, a nipper-lever fast on said shaft, said nipper-lever being forked with one of its arms co-operating as an abutment with said member, and a spring connecting the other arm 95 of said nipper-lever with said member and maintaining the latter against said abutment.

3. In a comber, the combination with nipper-knives of a number of combing heads, 100 a nipper shaft, and connections between said nipper-shaft and nipper-knives, of a nipper-cam, a member fulcrumed on said shaft and reciprocated by said cam, a forked 105 nipper-lever fast on said shaft and comprising a short arm and a long arm, said short arm co-operating as an abutment with said member and the latter being extended beyond its point of engagement with said cam away from said long arm, and a spring connecting such extension of said member with 110 said long arm and constituting a yielding driving connection therebetween normally holding said short arm in contact with said member.

In testimony whereof, I have signed this specification in the presence of two witnesses.

HENRY A. OWEN.
